UNITED STATES PATENT OFFICE

ALEXANDRE M. GREAN, OF NEW YORK, N. Y.

LEG-COVERING MEANS.

1,106,375.

Specification of Letters Patent. Patented Aug. 11, 1914.

Application filed August 2, 1913. Serial No. 782,648.

To all whom it may concern:

Be it known that I, ALEXANDRE M. GREAN, a citizen of the United States, residing at New York, in the county of New York and 5 State of New York, have invented new and useful Improvements in Leg-Covering Means, of which the following is a specification.

As is well known, by the present decree of 10 fashion, the skirts of female wearing apparel are cut or slashed from the bottom upwardly a considerable distance, and said skirts being narrow, as a consequence, it follows that the lower parts of the legs of the 15 wearer are exposed when walking or mounting steps and the like.

The present invention aims to provide 20 novel means of a simple character, which may be applied directly to the portion of the leg that is thus exposed by the skirt, and will hide the same from gaze.

An embodiment of the invention is illustrated in the accompanying drawings, but it will be obvious that various modifications 25 may be made from the same without departing from the scope of the invention.

In said drawings, Figure 1 is a side elevation, showing the article applied. Fig. 2 is an elevation of a portion of the article 30 viewed from the inner side. Fig. 3 is a vertical sectional view on the line 3—3 of Fig. 2. Fig. 4 is a horizontal sectional view. Fig. 5 is a view similar to Fig. 2, but showing a form of fringe made up of a large 35 number of strands or threads.

Similar reference numerals designate corresponding parts in all the figures of the drawings.

In the particular embodiment illustrated, 40 a leg-encircling garter formed of an elastic strap 5, is employed, having a socket clasp element 6 at one end and a coacting head element at the other that is arranged to detachably interlock with the socket element. 45 Carried by the elastic strap and secured to one face of the same, preferably by sewing, is an ornamental body 8 that is extensible, to permit the necessary elongation and contraction of the strap 5. Secured to the opposite face of the said strap 5, preferably by stitching, is leg-covering means that may be

in the form of fringe 9 that is thus carried by the strap, and depends below the same and below the said body 8.

In use, the garter is placed about the leg 55 above the calf, being secured by the interlocking engagement of the clasp elements 6 and 7. The fringe or leg-covering means 9 is of sufficient length to extend substantially to the ankle, and thus covers or hides the leg, 60 without in any manner interfering with its movements, and being also independent of the skirt.

While the device is particularly intended 65 for use in connection with a narrow skirt having a longitudinal slit or slash at its lower portion, it may of course be employed with short skirts, or in fact with any type of skirt. For example, it would hide the lower part of the leg when a skirt is lifted. 70

From the foregoing, it is thought that the construction, operation and many advantages of the herein described invention will be apparent to those skilled in the art, without further description, and it will be understood that various changes in the shape, size, 75 proportion and minor details of construction may be resorted to without departing from the spirit or sacrificing any of the advantages of the invention. 80

Having thus fully described my invention, what I claim as new and desire to secure by Letters Patent, is:—

1. As an article of manufacture, a leg-covering device comprising a leg-encircling 85 garter and leg-covering means secured thereto and depending loosely therefrom to encircle the leg and conceal the shape thereof.

2. As an article of manufacture, a leg-covering device comprising a garter arranged to encircle the leg above the calf 90 thereof, and leg-covering means loosely suspended from the garter and of sufficient length to extend substantially to and terminate at the ankle of the wearer, said means 95 loosely surrounding the leg and concealing the shape thereof.

3. As an article of manufacture, a leg-encircling garter consisting of an elastic strap having detachably interlocking head 100 and socket clasps at its ends, an extensible body arranged over and longitudinally of

the elastic strap, and leg-hiding fringe secured to the elastic strap in rear of the body and depending below the same and below the strap, said fringe being of sufficient length 5 to extend substantially to and terminate at the ankle and hiding the shape of the leg.

In testimony whereof I have hereunto set

my hand in presence of two subscribing witnesses.

ALEXANDRE M. GREAN.
